UNITED STATES PATENT OFFICE.

FRIEDRICH KUHLES, OF MAYWOOD, NEW JERSEY.

NON-REFILLABLE BOTTLE.

1,157,164.

Specification of Letters Patent.

Patented Oct. 19, 1915.

Application filed June 11, 1915. Serial No. 33,445.

To all whom it may concern:

Be it known that I, FRIEDRICH KUHLES, a citizen of the United States, and a resident of Maywood, in the county of Bergen and State of New Jersey, have invented certain new and useful Improvements in Non-Refillable Bottles, of which the following is a specification.

This invention relates to a non-refillable bottle, which is of simple construction and reliable in operation.

In the accompanying drawing: Figure 1 is a longitudinal section of the upper part of a bottle embodying my invention; Fig. 2 a side view of the sleeve; Fig. 3 a cross section on line 3—3 Fig. 1, and Fig. 4 a cross section on line 4—4 Fig. 1.

The device comprises essentially a tubular sleeve 1, fitted into the neck 2 of a bottle 20 3, and of such a diameter as to form an annular discharge passage 4 therebetween. At its lower edge this passage is closed by an annular packing ring or flexible gasket 5 that is seated within a groove 6 of neck 2, 25 and serves as a means for centering the sleeve within the neck. Within sleeve 1 is accommodated, a freely movable float valve 7 which is adapted to rest upon a seat 8 formed within the lower part of the sleeve. 30 This valve is composed of a hollow sphere of glass, or similar material, which is adapted to float upon the liquid, and will not injuriously affect the same. Within sleeve 1 is further accommodated, a freely movable 35 weight 9 which is likewise composed of a sphere of glass or similar material, but is made solid, so that it will not float upon the liquid. Weight 9 rests normally on float 7, as indicated in Fig. 1.

40 Into the top of sleeve 1, there is fitted, a plug 10, having a number of ports or apertures 11, and provided with a neck carrying a disk 12, that is slightly larger than the diameter of sleeve 1, so as to prevent tampering with the contents of the sleeve. When the bottle is righted, weight 9 will rest on float 7, and the latter in turn will rest on

seat 8. When the bottle is tilted, weight 9 will descend until checked by plug 10, float 7 will relinquish seat 8, and the liquid may 50 be freely poured out. Refilling of the bottle when the latter is in an upright position, is of course prevented, owing to the fact that the float becomes re-seated. When the bottle is, for refilling purposes, tilted with its 55 neck held downward, the float will rise with the ingress of the liquid and settle against seat 8. When the bottle is, for refilling purposes, tilted with its neck held upward, the weight 9 will descend and thus 60 force the float against the seat. In this way, the spurious refilling of the bottle in all positions, is prevented in a neat and reliable manner, while the outflow of the liquid is in no wise unduly hampered. To assemble the parts, gasket 5 is slipped over sleeve 1 so as to rest upon a bottom flange of the same, while plug 10 is introduced into the top of the sleeve, with its neck and disk extending beyond the top thereof. The 70 sleeve is now lowered into the bottle neck, during which operation the gasket 5, will be accommodated by clearance 4, within which it is compressed, until it reaches groove 6, where it will expand to lock the sleeve to the 75 bottle. The disk 12 by extending across the bottle neck over passage 4, will prevent the introduction of a tool for the purpose of tampering with the device.

I claim:

80 A non-refillable bottle having a neck provided with a lower groove, a sleeve centered within said neck and of a diameter to form an annular passage therebetween, a flexible gasket encircling the sleeve and adapted to 85 be projected into said lower groove through said annular passage, a valve seat formed in the sleeve, a spherical float adapted to engage the seat, a spherical weight adapted to engage the float, an apertured plug fitted 90 into the top of the sleeve, a neck extending upwardly from the plug, and a disk carried by the neck and projecting over the sleeve.

FRIEDRICH KUHLES.
